CLAIM

I claim the ornamental design for a trellis, as shown and described.

DESCRIPTION

FIG. 1 is a front view of a trellis showing my new design;
FIG. 2 is a rear elevational view thereof;
FIG. 3 is a first side view thereof;
FIG. 4 is a second side elevational view as seen from the side
opposite of that of FIG. 3;
FIG. 5 is a top view thereof;
FIG. 6 is a bottom view thereof; and,
FIG. 7 is a perspective view thereof.
